MULTIWAVE RANGE RECEIVER

Erich Zepler, Berlin, Germany, assignor to Telefunkens Gesellschaft für Drahtlose Telegraphie m. b. H., Berlin, Germany, a corporation of Germany

Application November 17, 1936, Serial No. 111,179
In Germany November 4, 1935

4 Claims. (Cl. 250—20)

In order to provide unicontrol tuning in radio receivers, it is known in the prior art to balance the input capacities of the oscillating circuits by special trimmers. For increasing the accuracy 5 trimmers are not only connected to the tuning condensers but special trimmers are provided for the individual coils of the different wave ranges which are brought in circuit whenever the coordinated wave range is cut-in and which are 10 the means to equalize the differences of the coil capacities in the individual wave ranges.

In the accompanying drawing Fig. 1 shows a circuit arrangement according to the prior art, and Fig. 2 discloses the improvement in such 15 circuit arrangement according to the present invention.

Referring to Fig. 1 the tuning condenser is denoted by C and the coordinated trimmer by C'. Special trimmers C₁ and C₂ are disposed in addition 20 across coils L₁ and L₂, these latter being switched in by switches S₁ and S₂ according to the wave range through which it is desired to tune.

In the case of a capacitative coupling of the 25 antenna through a condenser C_A, trimmer C' in the input circuit is omitted but used in the subsequent circuits, for capacity C_A is actually connected in parallel with the oscillation circuit through the antenna-earth capacity. Now, it 30 would be desirable to omit also the trimmers C₁ and C₂ since in that case the coupling capacity C_A could be correspondingly increased. This is not feasible however, as the self-capacity of coils L₁ and L₂ can be smaller than that of the coils 35 in the subsequent circuits so that the trimmers still have to be utilized.

According to the invention, in multi-circuit receivers with special trimmers connected to the coils of different wave range, the coil trimmers 40 of the input circuit each have one side connected to the grid end of its associated coil, and its other side connected through the wave range switch to the antenna instead of to the grounded end of the coil or input circuit.

Fig. 2 shows an exemplified embodiment of the 45 invention. It may be seen that the lower connections of trimmers C₁ and C₂ are connected to the contacts of switch S₃ and that with the switching in of different wave ranges the corresponding trimmer is connected in parallel with coupling condenser C_A. The coupling of the antenna is therefore made closer without increasing the initial capacity of the circuits. In fact, the initial capacities of the input circuits 50 must not be increased at will otherwise the wave

ranges would be considerably restricted with a given minimum capacity of the rotary condensers.

For greater clarity, it is to be noted that the invention refers expressly to multi-stage receivers 5 and to a capacitive antenna coupling in such receivers. The purpose of the invention consists in increasing the antenna coupling and thereby the volume without the necessity of increasing the incipient capacitances of the tuning circuits. 10 To be sure, the antenna coupling condenser C_A has to be considered as incipient capacitance of the first tuned circuit. The solution consists, as compared to the known arrangement according to Fig. 1, in not coupling the coil trimmers C₁, C₂ 15 tightly to the single coils of the various wave ranges but in connecting said trimmers according to Fig. 2 in parallel to the coupling condenser C_A. The condenser C_A is, of course, unnecessary if the capacitances C₁ and C₂ are chosen corre- 20 spondingly large. This possibility has heretofore been mentioned. However, in the arrangement according to the invention (Fig. 2), the condenser C_A is provided for the sole reason that then the variable capacitances C₁ and C₂ need not 25 be too large. They are only intended for balancing the small difference of the coil capacitances.

The invention is not limited to the type of coil switching circuit as illustrated but may be applied to rotary coil systems or switching operations by short-circuiting a part of the coils or to plug coils whereon the coil trimmers are disposed. In the latter case the plugs and plug 30 sockets may be considered as a wave switch.

Having described my invention, what I claim 35 as novel and desire to secure by Letters Patent is:

1. In a radio receiver, the combination of a vacuum tube having a cathode, grid and plate, an adjustable tuning condenser connected between said grid and cathode, a coil shunted across 40 said tuning coil to the opposite sides of said condenser, an antenna, a circuit including a coupling capacity connecting said grid and said antenna, and a condenser having one side connected to the grid end of said tuning condenser 45 and its other side to said antenna, whereby said last mentioned condenser is effectively in shunt to said antenna coupling capacity.

2. In a radio receiver, the combination of a vacuum tube amplifier having a cathode, grid 50 and anode, an adjustable tuning condenser connected between said grid and cathode, a coil having its terminals connected between the opposite sides of said condenser, an antenna, a fixed condenser connected to said antenna and grid, and 55

a variable condenser connected in shunt with
said fixed condenser, said fixed condenser,
variable condenser and the capacity of said
antenna together constituting a trimmer capacity
5 adapted to adjust the tuning of the circuit com-
prising said coil and adjustable tuning condenser
to a predetermined frequency.

3. In a radio receiver, the combination of a
vacuum tube amplifier having a cathode, grid
10 and anode, an adjustable tuning condenser con-
nected between said grid and cathode, a plurality
of coils having different inductance values,
means for selectively connecting the terminals of
anyone of said coils between the opposite sides of
15 said tuning condenser, an antenna, a plurality
of adjustable condensers, one for each of the
coils, and a switching device arranged to selec-
tively connect an appropriate one of said last
named condensers depending upon the selector
20 coil, in series between said antenna and said
grid.

4. In a radio receiver, the combination of a
vacuum tube having a cathode, grid and plate,
an adjustable tuning condenser connected be-
tween said grid and cathode, a plurality of coils
having different inductance values, a switching
5 device for selectively connecting the terminals
of anyone of said coils between the opposite sides
of said tuning condenser, an antenna, a coupling
condenser connected between said antenna and
grid, a plurality of adjustable trimmer condensers,
10 one for each of the coils, a connection from
one side of each trimmer condenser to the high
potential end of the corresponding coil, and a
second switching device for selectively connect-
ing the other side of the selected trimmer con-
denser to the antenna, said switching devices
15 being controlled to operate in unison.
